UNITED STATES PATENT OFFICE.

JOHN WILLIS GARDNER, OF QUINCY, ILLINOIS.

COMBINED SPEED AND PRESSURE GOVERNOR.

SPECIFICATION forming part of Letters Patent No. 673,575, dated May 7, 1901.

Application filed February 20, 1901. Serial No. 48,037. (No model.)

To all whom it may concern:

Be it known that I, JOHN WILLIS GARDNER, of Quincy, in the county of Adams and State of Illinois, have invented certain new and useful Improvements in a Combined Speed and Pressure Governor; and I do hereby declare that the following is a full, clear, and exact description thereof, reference being had to the accompanying drawings, and to the letters of reference marked thereon, which form a part of this specification.

This invention relates to improvements in combined speed and pressure governors of that class shown in my prior United States Letters Patent, No. 638,412, granted December 5, 1899, and which are adapted to be applied to engines employed for operating air-compressors or other fluid-pumps and so constructed and connected with the engine and the receiver into which the fluid is being pumped that the speed of the engine may be regulated to correspond with the pressure in said receiver.

The present improvements are designed to improve the general construction and operation of governors of this character; and the invention consists in the matters hereinafter set forth, and more particularly pointed out in the appended claims.

In the drawings, Figure 1 is a side elevation of a combined speed and pressure governor made in accordance with my invention. Fig. 2 is a similar view, partly in section, with some of the parts in changed positions. Fig. 3 is a fragmentary sectional view on line 3 3 of Fig. 4. Fig. 4 is a fragmentary sectional view on line 4 4 of Fig. 2.

First referring to the general construction of the device, A designates a valve-chamber adapted to contain the usual governor-controlled throttle-valve. Said valve-chamber supports a frame consisting of two rising laterally-separated frame members B B, which latter support the principal parts of the valve mechanism. Said frame members are joined at their upper ends to a vertical bearing-sleeve B', located centrally over the valve-chamber. Said sleeve receives a tubular rotary shaft B², which supports at its upper end the usual centrifugally-acting weights B³, and which tubular shaft receives the governor-spindle B⁴, connected with and actuated

by said weights in the usual manner. The shaft B² is rotated through the medium of bevel gear-wheels b b', one affixed to said shaft and the other to the inner end of a horizontal rotative shaft B⁵, mounted in a bearing-sleeve formed on one of the frame members B and provided at its outer end with a belt wheel or pulley. C designates a short vertically-swinging lever which is pivoted between its ends to one of the rising frame members B and extends inwardly and adapted for connection at its inner end with the governor-spindle, below the gear-wheel thereon. The said lever C is herein shown as forked at its inner end, and the forked ends of the lever pass on opposite sides of a block or enlargement B⁶, attached to or formed on the lower end of the governor-spindle, and engage downwardly-facing shoulders b² thereon. Said lever is placed under the influence of a spring which resists the depression of the governor-spindle. As herein shown, the outer end of the lever is engaged by a spring-pressed device consisting of an endwise-movable rod D, which engages at its lower end said lever and bears downwardly thereon under the action of a spiral expansively-acting spring D', which surrounds said rod. Said rod passes at its upper end through a sleeve D², which has screw-threaded engagement with a horizontal part b³ of the adjacent frame member B, said stud being provided at its upper end with a polygonal head for engagement by a wrench. Said spring D' is interposed between the sleeve D² and an enlargement d at the lower end of the rod, whereby the tension of the spring may be varied to resist to a greater or less degree the action of the weights to depress the governor-spindle, the adjustment being effected by turning the screw-threaded sleeve inwardly and outwardly with respect to the frame. As herein shown, the block B⁶ is made separate from the governor-spindle, being provided at its upper end with an upwardly-opening recess which receives the lower end of the spindle. As the inner end of the lever is forced constantly upward by the spring D' the spindle and block need not be attached one to the other; but said spring D' acts to hold said parts in their proper operative relation. The part of the frame B on which the lever C is mounted is

chambered to inclose the inner end of said lever and the spring-actuating device therefor.

Referring now to the parts constituting and associated with the pressure-governor, E designates a cylinder mounted on a ledge b⁴, consisting of a lateral extension of the upper wall of the valve-chamber. Said cylinder is adapted for communication with the fluid-receiver through a pipe e, leading into the lower end 10 of the cylinder. E designates a piston in said cylinder, provided with a stem which rises upwardly therefrom and passes through the upper cylinder-head. F designates a lever which is pivoted between its ends to the same 15 frame member with which the lever C is connected, said lever F being below and generally parallel with the lever C. The lever F engages at its inner end a head B⁷, attached to the upper end of the valve-spindle B⁸, and 20 the opposite end of the lever is located over the piston-stem E² and adapted to be engaged thereby when the piston rises under the pressure of air entering said cylinder below the piston. The valve-stem is therefore depressed 25 when the piston is elevated. As herein shown, said head B⁷ of the valve-spindle is provided with a laterally-open socket, and the adjacent end of the lever F is suitably formed to engage said socket. The upper end of the valve- 30 spindle is screw-threaded and engages a screw-threaded aperture in the lower end of the head, and the head is provided at its upper end with a short guide-stem b⁵, which engages a guide-aperture in the lower end of the block 35 B⁶, connected with the governor-spindle. Said guide connections are provided to maintain the parts in proper alinement one with the other. Said valve-spindle is returned to its normal uppermost position after the same has 40 been depressed by the pressure of air within the receiver in the manner described through the medium of a spring-actuated endwise-movable rod G, which is supported in the adjacent frame member B and engages at its 45 lower end the outer end of the valve-spindle lever F. As herein shown, said rod passes at its upper end through a sleeve B⁹, which has screw-threaded engagement with the horizontal part b⁸ of said frame member B, and a spiral expansively-acting spring G' is interposed 50 between said sleeve and a head g on the lower end of said rod. The chambered part of said frame member B, which contains the spring-pressed rod D, is made sufficiently large to 55 contain said rod G and its actuating-spring.

In order that the pressure-governor may not be operated under the influence of ordinary pressure within the receiver, resistance to the rise of the piston in the cylinder is provided, which consists in this instance of a lever H, pivoted at its inner end to the stud f, which connects the lever F to the frame and rests between its ends upon the upper end of the piston-stem. Preferably said lever is 60 bifurcated at its inner end and passes upon both sides of the frame member B, to which it is pivoted, and the outer end of the lever

F is located between said arms of the bifurcated lever. As a means of varying the initial pressure at which the pressure-governor 70 is actuated the outer end of said lever is provided with a weight H, which is affixed thereto through the medium of a hand-screw h.

In order to prevent the pressure-governor bringing the engine to a full stop, I have provided means for limiting the closing movement thereof before this condition is brought about. The means shown consists of a screw-threaded bolt I, which is mounted in a projecting part b⁶ of the frame member B above 80 the resistance-lever H and is adapted to be engaged at its lower end by said lever H when the latter is raised by pressure of air within the cylinder E. Said bolt having screw-threaded connection with the frame permits 85 the minimum speed of the engine to be varied to suit different requirements, such variation being afforded by adjustment of the bolt toward and away from the lever H.

The operation of the device as constructed 90 and described may be briefly stated as follows: Fig. 1 shows the device at rest, with the weights D³ in their lowermost positions and the piston E' occupying the lower end of the cylinder E. The inner ends of the levers 95 C and F are elevated by the action of their springs D' G', whereby the valve-spindle and connected valve, as well as the governor-spindle, are in their raised or opened positions. At this time also the resistance-lever H is 100 resting on the upper end of the piston-stem, together with the outer end of the lever F. If the speed-governor be brought into operation by an excessive speed of the engine, as shown in Fig. 2, the weights B³ will be raised 105 and will act to depress the governor and valve spindle, the motion of the governor-spindle being communicated to the valve-spindle through the block B⁶, attached to the lower end of said governor-spindle, and the head B⁷, connected to the upper end of the valve-spindle. The centrifugal weights are elevated and the governor and valve spindles depressed against the force of the springs D' 110 and G, and upon the resumption of the normal speed of the engine the weights B³ fall 115 and the valve-spindle is moved upwardly to open the valve by the lever F under the action of the spring G', the opening movement of said lever being limited by contact of its outer end with the upper end of the piston-stem. The parts are so disposed that the head B⁷ and the block B⁶ of the valve and 120 governor spindles, respectively, are in contact with each other when the governor is at rest, as shown in Fig. 1, so that the valve will respond accurately and promptly to the action of the speed-governor.

The operation of the pressure-governor alone is as follows: Assuming that the parts 125 are in a position shown in Fig. 1 and the pressure of the air in the cylinder E below the piston E' is sufficient to overcome the resistance exerted by the weighted lever H, the

piston rises and projects the stem upwardly through the cylinder-head. Said stem being in contact with both the lever H and the lever F, said levers are simultaneously raised. 5 The elevation of the outer end of said lever F depresses the inner end thereof and the valve-spindle connected therewith. The depression of the valve-spindle by said lever F does not, however, depress the governor-spindle, as said parts have relatively vertical movement. The actions of the pressure and speed governors are therefore independent of each other, and both governors are constructed to quickly respond to the action of 15 the engine and to the pressure within the receiver. The lever H and weight H', as before stated, are merely for the purpose of providing a convenient means for determining the initial pressure within the receiver at which 20 the pressure-governor shall act and may be made of other form.

It is obvious that the construction herein illustrated may be varied without departing from the spirit of my invention, and I do not 25 wish to be limited to such construction except as hereinafter made the subject of specific claims.

I claim as my invention—

1. A combined speed and pressure governor 30 comprising, in combination with relatively endwise-movable governor and valve spindles, a spring applied to the governor-spindle to resist depression thereof, a fluid-pressed part acting on the valve-spindle in a manner 35 to depress the same, a spring acting in opposition to the fluid-pressed part, and means for varying the tension of the governor-spindle spring.

2. A combined speed and pressure governor 40 comprising, in combination with relatively endwise-movable governor and valve spindles, a spring applied to the governor-spindle to resist depression thereof, a fluid-pressed part acting on the valve-spindle in a manner 45 to depress the same, a spring acting in opposition to said fluid-pressed part and in conjunction with the governor-spindle spring, and means for varying the tension of the governor-spindle spring.

50 3. A combined speed and pressure governor comprising, in combination with relatively endwise-movable governor and valve spindles, a lever pivoted between its ends and connected at one end with the governor-spindle, a spring applied to the other end of said lever to depress the same, a second lever pivoted between its ends and connected at one end with the valve-spindle, a fluid-pressed part acting on said last-mentioned lever to 55 depress the valve-spindle, a spring applied to said lever and acting in opposition to said fluid-pressed part and also in conjunction with the governor-spindle spring.

4. A combined speed and pressure governor 60 comprising, in combination with relatively endwise-movable governor and valve spindles, a lever pivoted between its ends and

connected at one end with the governor-spindle, a spring applied to the other end of said lever to depress the same, a second lever pivoted between its ends and connected at one end with the valve-spindle, a fluid-pressed part acting on said last-mentioned lever to depress the valve-spindle, a spring applied to said lever and acting in opposition to said fluid-pressed part and also in conjunction with the governor-spindle spring, and means for varying the tension of said governor-spindle spring. 70

5. A combined speed and pressure governor 80 comprising, in combination with relatively endwise-movable governor and valve spindles, a lever pivoted between its ends and connected at one end with the governor-spindle, a spring applied to the other end of said lever to depress the same, a second lever pivoted between its ends and connected at one end with the valve-spindle, a fluid-pressed part acting on said last-mentioned lever to depress the valve-spindle, a spring applied 85 to said lever and acting in opposition to said fluid-pressed part and also in conjunction with the governor-spindle spring, and means for varying the minimum pressure at which 90 said fluid-pressed part shall be actuated. 95

6. A combined speed and pressure governor comprising, in combination with relatively endwise-movable governor and valve spindles and a governor-supporting frame, a lever pivoted between its ends to said frame and connected at one end with said governor-spindle, a rod engaging the other end of said lever and having sliding engagement with the frame, a spring applied to said rod to depress the outer end of said lever, a second lever 100 pivoted between its ends to said frame and connected at one end with the valve-spindle, a fluid-pressed part acting against the other end of said last-mentioned lever in a manner 105 to depress said valve-spindle, a rod engaging said lever, and having sliding engagement with the frame, and a spring applied to said rod and acting in opposition to the fluid-pressed part, and in conjunction with the governor-spindle spring. 110

7. A combined speed and pressure governor comprising, in combination with relatively endwise-movable governor and valve spindles and a governor-supporting frame, a lever pivoted between its ends to said frame and connected at one end with said governor-spindle, a rod engaging the other end of said lever and having sliding engagement with the frame, a spring applied to said rod to depress the outer end of said lever, a second lever 120 pivoted between its ends to said frame and connected at one end with the valve-spindle, a fluid-pressed part acting against the other end of said last-mentioned lever in a manner 125 to depress said valve-spindle, a rod engaging said lever, and having sliding engagement with the frame, a spring applied to said rod and acting in opposition to the fluid-pressed part, and in conjunction with the governor-spindle spring. 130

spindle spring, and means for varying the tension of the governor-spindle spring.

8. A combined speed and pressure governor comprising, in combination with governor and valve spindles, one of said spindles being provided with a guide-stem which engages a socket in a part connected with the other spindle and permitting relative endwise movement of the spindles, a lever pivoted between its ends and connected at its inner end with the governor-spindle, a spring applied to the outer end of said lever and acting to resist depression of said spindle, a second lever pivoted between its ends and connected at its inner end with the valve-spindle, a fluid-pressed part acting on the outer end of the lever in a manner to depress the valve-spindle, and a spring applied to said last-mentioned lever, which acts in opposition to the fluid-pressed part and in conjunction with the governor-spindle spring.

9. A combined speed and pressure governor comprising, in combination with relatively endwise-movable governor and valve spindles, a spring applied to the governor-spindle in a manner to resist depression of the spindle, a lever pivoted between its ends and engaging at one end the valve-spindle, a fluid-pressed part acting on the other end of

said lever in a manner to depress the valve-spindle, a spring applied to said lever and acting in opposition to said fluid-pressed part and also in conjunction with the governor-spindle spring, and a weight or its equivalent applied to said fluid-pressed part which acts in opposition to the fluid-pressure against said part.

10. A combined speed and pressure governor comprising, in combination with relatively endwise-movable governor and valve spindles, a spring applied to the governor-spindle in a manner to resist depression of said spindle, a fluid-pressed part acting on the valve-spindle in a manner to depress the same, a spring acting in opposition to the fluid-pressed part and in conjunction with the governor-spindle spring, and an adjustable stop for limiting the movement of the fluid-pressed part which depresses the valve-spindle.

In testimony that I claim the foregoing as my invention I affix my signature, in presence of two witnesses, this 2d day of February, A. D. 1901.

J. WILLIS GARDNER.
